UNITED STATES PATENT OFFICE.

JACOB PEASE, OF BROOKLYN, ASSIGNOR OF ONE-HALF TO WILLIAM BROOKFIELD, OF NEW YORK, N. Y.

GLASS-FURNACE.

SPECIFICATION forming part of Letters Patent No. 416,703, dated December 3, 1889.

Application filed July 17, 1886. Serial No. 208,271. (No model.)

To all whom it may concern:

Be it known that I, JACOB PEASE, a citizen of the United States, residing at Brooklyn, in the county of Kings and State of New York, 5 have invented new and useful Improvements in Glass-Furnaces, of which the following is a specification.

This invention has for its objects to provide a novel glass-furnace whereby several persons 10 can work about the same furnace, and to provide a novel arrangement of flues and glass-receiving wells or pockets. These objects I accomplish in the manner and by the construction of parts hereinafter described and 15 claimed, reference being made to the accompanying drawings, in which—

Figure 1 represents a transverse section in the plane $\alpha\alpha$, Fig. 2, of a furnace embodying 20 my invention. Fig. 2 is a central vertical section of the same.

Similar letters indicate corresponding parts.

In the drawings, the letter A designates the walls of a furnace, which are constructed to contain a glass-forming chamber B, a fire-place C, and a stack D, as usual. In the glass-forming chamber B is constructed a circular hearth or basin E, into which the charge is introduced through an opening E', Fig. 1, that can be subsequently closed in the ordinary 30 manner. Above this hearth or basin and closing the glass-forming chamber from the stack is an arch A'. Surrounding the hearth or basin and exterior to the walls of the same are a number of wells or pockets F, which are closed at their tops and bottoms, and each of 35 which is connected with the hearth or basin by a duct or ducts f, extending through the furnace-walls and connecting the respective well and hearth near their bottoms, so that 40 the level of the molten mass will be the same in both wells and hearth.

In order that the molten mass may not be cooled when in the wells, I lead the furnace-gases from the glass-forming chamber around 45 the exterior of the wells, and from thence into the stack.

In the example shown in the drawings, Fig. 2, flues g lead from the glass-forming chamber over the top of the well and connect with 50 vertical flues g', Figs. 1 and 2, which extend

down the back of the well. These flues g' communicate with a bottom flue h, Fig. 1, from which in turn lead flues h', that pass along both sides of the well and are either led directly to the stack above the arch A', 55 or, as shown, they are received by a common flue H, which leads to the stack above the arch. By this arrangement of flues all the furnace-gases must necessarily pass around the wells before they can pass to the stack, 60 and as the flues almost surround the wells or pockets said wells or pockets receive all the necessary heat to keep the mass in a molten state. To remove the molten glass from the wells or pockets, I construct tubular mouths 65 f', which lead from the same to the exterior of the furnace. I use tubular mouths for the reason that it is necessary to cut the same through the flue-spaces.

The advantages of a furnace embodying 70 my construction are that more men can work at one and the same furnace than hitherto and a pure clear glass is produced.

What I claim as new, and desire to secure by Letters Patent, is—

1. The combination, in a glass-furnace, of a circular hearth or basin E, for receiving the charge, a closed arch A' over the hearth or basin, a stack D, located over the arch, a series of glass-working wells F, disposed around 80 the hearth or basin, a flue f for each individual well connecting it with the hearth or basin, and ducts leading the furnace-gases around each well to the stack above the arch, substantially as described. 85

2. The combination, in a glass-furnace, of a circular hearth or basin E for receiving the charge, a stack D, a series of glass-working wells or pockets F, projecting from and arranged exterior to the wells of the furnace 90 around the hearth or basin, a duct f for each pocket arranged in the furnace-wall and communicating directly with the basin, the mouths f' for removing the molten mass from the pockets, and flues g, extending over 95 the pockets and communicating with the stack, substantially as described.

3. In a glass-furnace, the combination, with a hearth or basin for receiving the charge, of a number of wells or pockets connected with 100

the hearth or basin, and the flues surrounding the pockets, substantially as shown and described.

4. In a glass-furnace, the combination, with
5 the arched glass-chamber and the stack, of a
hearth or basin in the glass-chamber, a num-
ber of wells or pockets connected with said
hearth, and flues communicating with the
glass-chamber below the arch, said flues sur-
10 rounding the wells or pockets and entering

the stack above the arch, substantially as shown and described.

In testimony whereof I have hereunto set my hand and seal in the presence of two sub-
scribing witnesses.

JACOB PEASE. [L.S.]
